UNITED STATES PATENT OFFICE.

ROBERT P. LYLE, OF PORTLAND, OREGON.

AUTOMATIC DENTAL HAMMER.

No. 927,420.

Specification of Letters Patent.

Patented July 6, 1909.

Application filed August 28, 1908. Serial No. 450,600.

To all whom it may concern:

Be it known that I, ROBERT P. LYLE, citizen of the United States, residing at Portland, in the county of Multnomah and State 5 of Oregon, have invented certain new and useful Improvements in Automatic Dental Hammers, of which the following is a specification.

This invention relates to improvements in 10 dental hammers and has for its object to provide an automatic hammer which may be used to hammer the filling on the inner side of the tooth.

Another object is to provide such a hammer 15 which may be cheaply manufactured and which is simple in construction.

These objects are attained by means of the 20 improvements illustrated in the accompanying drawings in which,

Figure 1 is a cross section through the center of the tool. Fig. 2 is an end view of the 25 inside of part 2. Fig. 3 is another sectional elevation showing the plunger pulled out in the direction of arrow —A— and also shows how part 11 is forced in the same direction by parts 13. Fig. 4 shows detail view of part 30 18. Fig. 5 is an end view of Fig. 4. Fig. 6 is an end view of Fig. 7. Fig. 7 shows detail view of part 13. Fig. 8 shows detail of part 23. Fig. 9 shows a different method of forcing the parts 13 apart.

Like numerals of reference indicate similar parts throughout the several views.

Referring to the drawings, there is shown a 35 hollow handle 1 which is threaded at one end as shown for the reception of cap 2 and has a portion of it bored out slightly more than the rest so as to form a shoulder at 3. An inner tube 26 is arranged to screw into cap 2 and is 40 slotted as shown at 8, a slightly rounded shoulder being formed at 9 for a purpose hereinafter mentioned. Part 11 is held against shoulder 3 by spring 10 and may be forced along the length of the enlarged hollow 45 portion of the handle 1 in the direction of arrow —A—. The plunger consists of a spindle portion 6 enlarged at 18 and provided with a head portion or shoulder 4. The small end of the plunger is arranged to hold 50 various hook-like tamping pieces 7 which in the present instance are shown screwed in. A hole 14 is drilled in the plunger for the reception of pin 23 which is shown in detail in Fig. 8. A spring is placed in the bottom of 55 hole 14 to force pin 23 outward. 18 is provided with a slot 19 for the reception of dogs

13 which are pivotally held in place by pin 12 and forced apart by pin 23. Dogs 13 are shown in detail in Figs. 6 and 7. In order that the two dogs may partially interlock so 60 that they may both be held on the same pin 12, a portion of the dogs is cut away as shown at 22 in Figs. 6 and 7.

In Fig. 9 is shown another method of forcing the dogs 13 apart. In this case a V shaped 65 spring is used instead of spring and pin 23. The plunger is forced toward the closed end of handle 1 by spring 17 and is held at rest there until the handle 1 is pulled in direction of arrow —B—, 7 being held stationary. As 70 the handle is drawn away from 7, the plunger assumes the position shown in Fig. 3, the dogs 13 being forced against 11 at 15. Shoulders 9 at the bottom of slots 8 force dogs 13 inward when the surface 16 of said dogs 75 comes in contact with said shoulders 9, thus causing shoulders 15 to release hammer ring 11 which is then forced against shoulder 4 of the plunger by spring 10 thereby causing the desired shock in the direction of arrow —B— 80 on tamping piece 7. As the handle 1 is brought forward again it allows the plunger to assume its former position, when the operation may be repeated. If desired, a plunger rod 27 may be screwed in end of enlarged portion 4 of plunger, or otherwise attached to same, and may extend through orifice 25 in handle 1. Tamping pieces may then be attached to the outer end of said plunger rod 27 for the purpose of filling the 85 outer side of the teeth.

It is understood that slight changes may be made in the specific structure shown without departing from the spirit of the invention.

What is claimed is;

1. An automatic dental hammer comprising 95 a stem adapted to carry a tool at either end, an inner casing, an outer casing, said casings surrounding the stem and adapted for movement independent thereof, and means adapted for travel on the inner casing to impart a blow to the stem by a movement of the outer casing in one direction.

2. An automatic dental hammer including an outer casing, an inner casing, a tool-carrying stem within the inner casing, means for imparting impact to the stem, means for normally locking the impact means against stem - influencing operation, and means formed integral with the inner casing for releasing said impact means.

3. An automatic dental hammer including

an outer casing, an inner casing, a tool-carrying stem within the inner casing, means for imparting impact to the stem, means for normally locking the impact means against stem-influencing operation, means carried by the inner casing for releasing said impact means, and means disposed within the stem to normally maintain said locking means in locking position.

10 4. An automatic dental hammer including a tool-carrying stem, an inner casing disposed about the stem, an outer casing disposed about the inner casing and adapted for movement independent of the stem, normally-inoperative means for imparting a blow to the stem adapted for travel on said inner casing, and means disposed about said inner casing for automatically inducing stem-influencing operation of said normally-inoperative means by movement of the outer casing in one direction.

25 5. An automatic dental hammer comprising a stem, a slotted inner casing surrounding the stem, an outer casing surrounding the inner casing, said stem and outer casing being adapted for independent movement, spring-influenced means for imparting a blow to the stem, stem-carried means adapted for travel in said slotted casing and operable in 30 the movement of the outer casing for operatively positioning said blow-imparting means under tension of said spring, and means carried by the inner casing to release said spring from tension.

35 6. An automatic dental hammer comprising a stem, an outer casing, an inner casing, said outer casing and stem being adapted for

independent relative movement, a spring-influenced annular member adapted in movement to impart a blow to the stem, and means carried by the stem to move said member to blow-imparting position against tension of said spring in the movement of the outer casing, and means carried by the inner casing to release said member from tension of said spring.

7. An automatic hammer comprising a stem, an outer casing, an inner casing, said casings being adapted for movement independent of the stem, a spring-influenced annular member adapted in movement to impart a blow to the stem, and a plurality of dogs carried by the stem to move said member to blow-imparting position against tension of said spring in the movement of the outer casing in one direction, and means carried by the inner casing to release said member from tension of said spring.

8. An automatic dental hammer comprising a stem, an outer casing, an inner casing, a spring-influenced annular member adapted in movement to impart a blow to the stem, a plurality of dogs carried by the stem to move said member to blow-imparting position against tension of said spring in the movement of the outer casing in one direction, and shoulders carried by the inner casing to release said member from tension of said spring.

In testimony whereof, I affix my signature in presence of two witnesses.

ROBERT P. LYLE.
